(57) **CLAIM**

The ornamental design for a bottle, as shown and described.

DESCRIPTION

FIG. 1 is a top view of a bottle showing my new design;

FIG. 2 is a front view thereof;

FIG. 3 is a right side view thereof; and,

FIG. 4 is a bottom view thereof.

The portions shown in broken lines are directed to the boundary of the design and form no part of the claimed design. The right side view is the same as the left side view and the rear view is the same as the front view.

1 Claim, 4 Drawing Sheets

FIG.1

FIG.2
